UNITED STATES PATENT OFFICE.

WILLIAM F. GARLAND, OF NEW YORK, N. Y.

PHOTOGRAPHIC DEVELOPING-MACHINE.

1,185,191.

Specification of Letters Patent. Patented May 30, 1916.

Application filed December 17, 1909. Serial No. 533,520.

To all whom it may concern:

Be it known that I, WILLIAM F. GARLAND, a citizen of the United States, residing at New York city, county of New York, and State of New York, have invented certain new and useful Improvements in Photographic Developing-Machines, fully described and represented in the following specification and the accompanying drawings, forming a part of the same.

10 This invention relates to a machine for developing, fixing and washing photographic films having a large extent of surface whether in the shape of long, narrow strips, such as are used for making negatives or positives of so-called moving pictures, or films whose dimensions in both directions are large, or for developing together a large number of smaller films.

15 The invention has been made especially with the idea of providing a machine for developing the long moving picture films, and one part of the invention relates especially to the handling of such films, but aside from this feature the invention will be found useful and is intended to use in developing other large films or a number of smaller films at one time, as above stated. In using the word "film" to describe the article or articles on which the machine or the invention is intended to operate, I intend this word to include not only the transparent sheets of coated celluloid or other substance to which the term is usually applied and which are employed for making negatives or transparent positives, but also to include sheets of paper or other material having a coated or otherwise sensitized surface, and which are usually employed for making positive prints from photographic negatives.

20 The object of the invention is generally to provide a photographic developing machine or apparatus by which films introduced into the machine will be subjected to the successive steps of developing, fixing and washing, and drying, if desired, either entirely without manipulation or attention by the operator during the performance of these successive steps of the treatment, the machine being entirely automatic in its operation, or with only such attention from the operator as is required to set into operation the mechanisms which cause the film carrier to be shifted from the station where

the next station; to avoid the necessity of handling the film from the time it is first placed on the carrier to be developed until it has been carried through the successive steps of developing, fixing, washing and drying; to avoid the necessity of manual transfer of the film carrier from one solution to another; to provide for either automatic control or control at will of the timing of the development and the strength of the developing solution; to secure a clean and uniform development with the use of a minimum quantity of solution; to effect the various steps in the process or treatment of the film with maximum economy in the use of solutions without sacrifice of efficiency; to provide a machine which shall be continuous in its operation on successive film carriers in such a way that a plurality of carriers may be passing through the machine at the same time, successive carriers being at the development station while preceding carriers are at the fixing and washing stations; and to provide for the winding of long narrow films on a carrying drum, which is the preferred form of film carrier, with uniform tension, so that it will maintain its position on the carrier during its progress through the machine.

25 To these ends and with other objects in view, the invention consists in the construction, arrangement and combinations of parts of a complete organized machine for developing, fixing, washing and drying photographic films, and of parts or features of such complete organized machine, as hereinafter fully described and specifically pointed out in the claims.

30 As a full understanding of the invention can best be given by a detailed description of a complete machine embodying the various features of the invention in a preferred form, such a description will now be given in connection with the accompanying drawings showing such a machine and in which—

35 Figure 1 is a plan view of the machine partly broken away and with parts such as the tanks and piping for supplying the developing, fixing and other solutions and the cooling water omitted. Fig. 2 is an elevation of the machine shown in Fig. 1. Fig. 3 is a plan view of the various developing, fixing and washing trays with the piping by which the water and solutions are supplied thereto. Fig. 4 shows in elevation the parts

shown in Fig. 3 together with certain additional parts shown in full lines, and with the track or runway for the carrying drums shown in dotted lines, and with the positions 5 of the carrying drums at the various stations at which they stop during their progress through the machine shown by dotted lines. Fig. 5 is an end view of the machine looking from the left in Figs. 1 to 4. Fig. 6 10 is a section on line 6 of Fig. 3. Fig. 7 is a section on line 7 of Fig. 3 and showing the lower part of a carrying drum in position. Fig. 8 is a detail sectional view on line 8 of Fig. 1. Fig. 9 is a broken sectional view on line 9 of Fig. 1. Fig. 10 is a section on line 15 10 of Fig. 1, showing the timing mechanism in elevation. Fig. 11 is a side view of the timing mechanism shown partly in section on line 11 of Fig. 1. Fig. 12 is an enlarged 20 modified sectional view of the timing mechanism taken on lines passing through the several axes and the contact pieces. Fig. 13 is a view in elevation of the portion of the machine indicated by the line 13 on Fig. 1 25 showing one of the shifting sections of the carrier drum track in its shifting position. Fig. 14 is a section taken on line 14 of Fig. 1 showing the first light door, its frame and operating connections. Fig. 15 is a detail 30 view of part of the film winding mechanism.

Referring first briefly to the general construction of the machine, the films to be developed are applied to the peripheral faces 35 of one or more carrier drums according to the amount of film to be developed. The carrier drums are then caused to advance step by step through the machine with their axes horizontal, and each drum as it is advanced through the machine is stopped at successive points or stations for predetermined or desired periods of time. At each such station the drum is caused to rotate with the lower portion of its film carrying 40 periphery dipping into a tank or tray containing the liquid or solution to the action of which the film is to be subjected at such station. The carrier drums are caused to advance between the stations by rolling on a 45 track or guideway which is made up of a succession of stationary inclined portions combined with suitable lifting devices at each station, which operate to lift the drums when they are to be advanced from one 50 station to the next to cause them to roll over the intervening inclined track to the next station. Such lifting devices may be operated manually by means of suitable hand levers, or may be automatically operated by 55 means controlled by a timing device which in the case of the lifting means for raising the drums from the developing station is preferably adjustable for varying the time of development as desired. The number of 60 stations at which the carrier drums are

stopped for treatment of the film may be varied according to the number of different operations to which it is desired to subject the films. I prefer, however, to arrange the machine so as to provide for a preliminary 70 wetting station, a developing station, a plurality of fixing stations, preferably three, and a plurality, as for example five, of washing stations. Separate tanks are provided for the preliminary wetting and the developing stations, and preferably a separate tank is provided for each fixing station, and a single long tank for the plurality of washing stations. Additional stations with their necessary tanks and fittings may, of course, be provided for subjecting the films to the action of other solutions which it may be desired to use in the process of developing and fixing, such as a glycerin solution which is sometimes used after the washing of the 85 film, or a hardening solution after the fixing and before the washing. It is common practice in the development of photographic films to wash the film between the developing and fixing steps of the process, and an intermediate washing station may, of course, be provided in the machine for this purpose. With my apparatus, however, in which both the developer and the fixing solution are constantly changing during the developing and fixing of the films, the danger of staining is practically if not entirely eliminated, and the principal reason for washing the film between developing and fixing is therefore avoided, and I therefore do not consider it 90 necessary to provide for the washing of the film between developing and fixing. 95

From the last washing station, the carrier drums pass into a drying room or chamber. Since development must take place in a so-called dark room or chamber from which the actinic rays of light are excluded, it is desirable to provide means for permitting the passage of the carrier drums from the dark room or chamber without admitting light to the dark room, and for this purpose automatically operated doors or shutters are preferably provided. Such shutters are best located beyond the last fixing station, and I prefer to place them between the last washing station and the drying chamber, although it will be understood that they may be otherwise located. 110

The tanks for the developing and fixing solutions at the developing and fixing stations are preferably made with their bottoms curved to correspond substantially with the curvature of the carrying surface of the drums, and are set relatively to the drum supporting and rotating devices so 125 that the film carrying surface of the drum will travel in close proximity to the bottom of the tank; and during the time that a drum is being rotated over each tank the solution is constantly supplied to that tank 130

at one point and escapes therefrom at another point. The treatment of the film with a constantly changing, and therefore always fresh and uniform solution, is thus secured, while at the same time the amount of solution necessary to be contained in the tank is so small that the total amount of solution required to be used is less than the amount required in developing according to the old methods and with the large tanks heretofore used.

5 A single carrier drum may be sent through the machine alone, making its various stops at the successive stations, or a plurality of carrier drums may be started successively and while others are still passing through the machine, so that a number of drums will be passing through the machine at the same time.

10 The machine is preferably provided with means for winding the long or moving-picture films on to the carrier drums, such means comprising a carrying and feeding device for the reel on which the film comes 15 from the camera or printing machine, and guiding means by which the film is guided from the moving reel to a drum which is being rotated at the wetting or receiving station located ahead of the developing station. 20 Drums carrying films other than the long or moving-picture films will also preferably be started in the machine at such receiving station so as to cause the films to be wetted before being advanced to the developing 25 station, so as to insure an even and uniform application of the developing solution thereto.

30 Referring now to the drawings, the carrier drums are advanced through the machine along two tracks or ways spaced according to the length of the carrier drums, and at intervals of the length of the tracks are arranged the drum-supporting and driving devices and the lifting devices of the 35 successive operating or resting stations at which the drums are arrested and rotated.

35 Each track is formed of a plurality of stationary sections 10, and a plurality of movable sections 11 one of which is pivotally mounted adjacent to the front end of each of the stationary sections. The front ends of the movable track sections 11 form the lifting devices by which the carrier drums are lifted from the supporting and 40 rotating devices at one station when they are to be advanced to the following station. The stationary sections 10 are inclined downwardly from front to rear, and each movable section 11 when in its elevated position as shown in Fig. 13, stands 45 in line with its corresponding stationary section 10 so as to form a continuous inclined rail or runway extending between adjacent drum stations. The front or movable ends of the sections 11 are formed with

upwardly extending shoulders 12, as shown clearly in Fig. 13, which serve to prevent back movement of the drums and to give the drums a quick forward start when the sections are lifted to their elevated position. 50 The stationary and movable sections of each track are shown as mounted between side plates or frames 13, which side plates or frames also serve to support most of the other operating parts of the machine. The 55 last stationary track sections 10 beyond the last drum station are shown as extended beyond the ends of the side plates 13 to form, or are arranged in line with, long inclined tracks 14 on which the drums roll past the 60 movable light shutters or doors and through the drying chamber, and these two tracks 14 are made of sufficient depth to have the required rigidity and to form a supporting means for operative parts of the machine located beyond the ends of the side plates 13. 65

The carrying drums 15 may be of any suitable or desired construction, but are preferably of ordinary squirrel cage construction, as indicated in detail in Fig. 9, 70 having end disks 16 connected by longitudinally extending peripheral bars 17 which form the supporting surface for the films, and having supporting trunnions 18 extending from the end disks. The trunnions 18 75 at each end of the drums are formed each with two guide flanges 19 spaced and located to correspond to the width and position of the tracks or runways, and with a supporting flange 20 beyond the flanges 19. The 80 ends of the films may be secured to the bars 17 of the carrier drums in any suitable manner, as by the use of suitable clips or hooks.

85 The machine as shown in the drawings has ten drum stations, marked A, B, C, D, 105 E, F, G, H, I and J, of which A is the preliminary wetting station and also the winding station for long films, B is the developing station, C, D and E the fixing stations, and F, G, H, I and J washing stations. 110 Each of the first five stations, as shown, is provided with separate tanks a, b, c, d, e, respectively; each of which is located so that a carrier drum rotating at the corresponding station will dip into liquid contained in the tank as it rotates; and a single long tank f is provided for the five washing stations. The means for supplying the various liquids and solutions to the several tanks and for maintaining the solutions in 115 the developing and fixing tanks at the desired temperature will be hereinafter described.

120 At each drum station there is provided at each side of the machine a pair of supporting and driving disks 21 and 22. These supporting and driving disks at each station are arranged with relation to the stationary track sections so that as a carrier drum advances and its trunnions pass be- 125 130

yond the end of the pair of track sections on which they have been running, the drum will drop until its supporting flanges 20 come into contact with the supporting and driving disks as shown in Fig. 2. The supporting and driving disks are formed with grooves to receive the drum flanges 20 and with gear teeth on either side of the grooves. To give better driving friction and to avoid all danger from sparking, the drum flanges 20 are preferably provided with rims or tires of rubber or other suitable friction increasing and non-sparking material. The gears of each pair of supporting and driving disks mesh with a driving gear 23 by which the supporting disks are continuously rotated.

Any suitable driving connection may be provided for operating the driving gears 23 at both sides of the machine. As shown, the gears are all driven from a main driving shaft 25 from which the driving gears 23 at each side of the machine at the developing station B are driven by vertically running sprocket chains indicated by the dotted lines 26 in Figs. 2 and 5. The driving gears 23 at the preliminary station A at each side of the machine are driven by means of sprocket chains 27 running on sprocket wheels on the shafts of the driving gears at the stations B and A, as shown in Fig. 1. The sprocket wheels on the shafts of the driving gears at the station A are shown larger than the driving sprockets for the chains 27 on the shafts of the gears 23 at the station B for the purpose of giving slower motion to the supporting and driving rolls at the station A. The driving gears 23 at the stations C, D, E, F, G, H, I and J are driven on the far side of the machine as it appears in Figs. 1 to 4 of the drawings, by means of a sprocket chain 28 running on sprockets on the shafts of the respective driving gears and on a driving sprocket on the shaft of the driving gear at station B, as shown in Fig. 1. On the near side of the machine, the driving gears at the stations C to J, inclusive, are connected by a sprocket chain 29 running on sprocket wheels on the shafts of the respective driving gears, and are driven by a vertically running sprocket chain 30 running on a wheel on the shaft of the driving gear 23 at the station C and on a sprocket wheel on a shaft 31 which is driven from the driving shaft 25 by means of a sprocket chain 32. This different arrangement of the driving connections on the near side of the machine is for the purpose of removing the driving connections from the timing devices.

Drums carrying films to be developed may be started in the machine at the developing station B, but in order to insure an even and uniform starting of the action of the developer on the film, it is desirable to have

the film moistened or wet before it is presented to the developing solution. This wetting of the film is effected at the station A. The films to be developed may be applied to the carrier drum before it is placed in position at the station A or while the drum is slowly rotating at such station, and special winding devices hereinafter described are provided at this station for winding the long moving picture films on 75 the drums.

The movable track sections 11 at the station A are normally in their depressed position, as shown in Fig. 2, and are raised from such position for causing the drums to advance from the station A to the developing station B at will by means of either one of a pair of hand levers 35 mounted on a transverse rock shaft 36 which also carries at each side of the machine a short arm 37 connected by a link 38 with the corresponding track section 11, so that if either of the hand levers 35 is thrown to the left, from the position shown in Figs. 1 and 2, the track sections 11 at the station A will be raised to elevate the carrier drum which has been rotating at the station A and lift its driving flanges 20 clear of the driving and supporting disks 21 and 22. The drum will then roll along the inclined track to 95 the developing station B where it will run from the end of the stationary track sections 10 and will come to rest with its driving flanges 20 on the supporting and driving disks 21 and 22 at this station. At each 100 of the stations B, C, D, E, F, G, H, I and J, one of the side plates or frames 13 at each side of the machine is formed with an upwardly extending stop shoulder 40 for preventing the drum coming to the station 105 from rolling beyond the station. Such stop shoulders are of such a height as not to interfere with the onward movement of the drums when they are raised by the movable track sections 11.

The movable track sections 11 at the developing station are each connected by a downwardly and rearwardly extending link 41 with a horizontally arranged movable rod 42 so that by a forward movement of 115 the rods 42 these movable track sections will be raised to lift the drum from the supporting and driving rolls at the developing station, and cause it to be advanced to the station C. Means are provided for giving 120 the required forward movement to the rods 42 either manually at will or automatically. For operating the rods 42 manually, hand levers 45 are provided carried by a transverse rock shaft 46 which also carries arms 125 47, each of which is connected by a link to one arm of a lever 48, the other arm of which extends downwardly in position to engage a collar 49 on the corresponding rod 42, as shown for one side of the machine in 130

Fig. 2. By throwing either of the hand levers 45 to the left in Figs. 1 and 2, the levers 48 will be operated to throw the rods 42 to the left and thereby cause the track sections 11 at the developing station to be elevated.

Automatic operation of the rods 42 for lifting the track sections at the developing station is effected in the machine shown 10 through the operation of electromagnets 50 and 51, the magnet 50 being in a position to attract an armature on the rod 42 at the near side of the machine in Figs. 1 and 2, and the magnet 51 being in position to attract an armature on the rod 42 at the far side of the machine. As shown, the magnets are of single spool form, having a central perforated core through which the rod 42 passes, and the armatures on the rods 42 15 are formed by the collars 49 above referred to. The magnets and their armatures are so shown for the sake of clearness in the drawings, and it will be understood, of course, that the arrangement, as by suitable 20 lever connections between the armatures and the rods 42 or other suitable expedient, should be such that the armatures will stand normally close enough to the magnets to be attracted thereby with sufficient 25 strength to effect the movement of the rods 42. For closing the circuits to the magnets 50 and 51 at the time when it is desired that development shall cease and the carrier drum should be advanced from the 30 developing station to the first fixing station, a timing mechanism is provided which is automatically set in operation when the carrier drum reaches the developing station and which is adjustable for varying the 35 time of development as desired.

A timing mechanism of preferred form is shown in Figs. 1 and 2 and in detail in Figs. 10, 11 and 12. This timing mechanism as shown also includes means for timing and 45 controlling the movement of the carrier rolls from the stations C to J inclusive. It will first be described with reference to the developing station. The timing mechanism includes an ordinary clock movement mounted 50 between supporting plates 55, said clock movement having a train of gears including a driven gear on an arbor 56 which carries two driving gears or pinions 57 and 58 and which may and as shown is intended to be 55 driven at a speed corresponding to the speed of the minute hand of a clock. The clock movement will be provided with a spring or other operating device of sufficient power to cause the movement of the parts of the 60 timing mechanism, and will operate constantly so that the driving gears 57 and 58 will be constantly rotating. A movable contact arm 60 carrying at its outer end an insulated contact piece 61 is mounted on a 65 short shaft 62 carried by an arm 63 which

extends downward from a rock shaft 64 and normally stands in the position shown in Fig. 11 when there is no carrier drum at the developing station. The arm 60 is normally held in the position shown in Fig. 11 70 by a weighted arm 65. The shaft 62 carries also a segment gear 66 adapted to engage with and be driven by the driving gear 57 but which when the arm 63 is in its normal position shown in Fig. 11 is out of engagement with the gear 57. The rock shaft 64 carries an arm 67 which extends forward inside the side pieces 13 on the near side of the machine in position to be engaged and depressed by the trunnion of a carrier drum 75 coming to position at the developing station. The downward movement of the arm 67 rocks the shaft 64 so as to throw the arm 63 upward to carry the segment gear 66 into engagement with the driving gear 57, by which 80 the gear 66 and shaft 62 will then be rotated to swing the contact arm 60 to the right. A stationary arm 68 is mounted so as to be adjustable about a pivot which stands in line with the shaft 62 when the latter is in 85 the position in which the gear 66 is in engagement with the driving gear 57, and this arm 68 carries an insulated contact piece 69 in position to be engaged by the contact piece 61 of the arm 60 as the latter arm is 90 moved to the right in Figs. 2 and 11 by the gears 57 and 66. A graduated dial plate 70 is preferably mounted between the arms 60 and 68, and its graduated scale is marked 95 with time divisions preferably corresponding to minute intervals, and is extended sufficiently to show the greatest number of minutes, as, for example, twenty, through which it may be desired to continue the development of a film.

The contact pieces 61 and 69 on the arms 60 and 68 respectively, are in electrical connection with a battery or other suitable source of electrical energy and with the two magnets 50 and 51, so that when the contact pieces are in engagement with each other the circuit will be closed through these magnets. As shown in the drawings, the stationary contact piece 69 is connected with one pole of the battery 71 by wire *l*, and the magnets 50 and 51 are connected in multiple with the other pole of the battery through wire *m*, and are also connected through wire *n* with the contact piece 61.

The parts of the device as above described 100 normally stand in the position shown in Fig. 11. When a carrier drum drops from the ends of the stationary rail sections to the supporting and driving disks at the developing station, the arm 67 is depressed and the arm 63 is thrown upward to carry the gear 66 into engagement with the driving gear 57, the parts being then in the position shown in Fig. 2. The gear 66 and shaft 62 105 will then be rotated to swing the arm 60 to 110 115 120 125 130

the right in Figs. 2 and 11 until its contact piece 61 comes into engagement with the contact piece 69 carried by the adjustable arm 68 and closes circuit to the magnets 50 and 51. The magnets will thereby be energized to attract the armatures 49 and thereby operate the rods 42 to cause the track sections 11 at the developing station to be raised to lift the carrier drum and cause it to roll bodily forward toward the station C. When the carrier drum is thus lifted, the arms 67 and 63 will be allowed to swing back under the influence of gravity or a suitable retracting spring to their normal position, disconnecting the gear 66 from the driving gear 57 and drawing the contact piece of the arm 60 out of engagement with the contact piece 69 to break the circuit to the magnets 50 and 51. The arm 60 will then be free to swing back under the influence of the weighted arm 65 to its normal vertical position as shown in Fig. 11, and the timing mechanism for the developing station and the parts which set it in operation will be then returned to normal position and ready for the next carrier drum which comes to the developing station. It will be seen that by adjusting the position of the stationary contact arm 68 to the right and downward in Fig. 11, the development period may be lengthened, and by adjusting the arm to the left and upward the period may be shortened, so that the timing device may be set to give any desired length of development within the capacity of the device as constructed, and that the development period will be timed from the moment a carrier drum comes into position at the developing station, and that at the end of the period for which the timing mechanism is set the developing drum will be automatically advanced from the developing station to the next station.

The means provided in the machine for operating the movable track sections at the several stations following the developing station, that is, at the fixing and washing stations in the machine shown, are similar to the means for raising the movable sections at the developing station, but are preferably arranged so that the movable track sections at all of such succeeding stations will be operated together. For this purpose, a single long horizontal operating rod 75 is provided at each side of the machine and to such rod at each side of the machine there are connected a number of connecting rods 76 one of which extends downwardly and rearwardly from each of the movable track sections at the stations C to J inclusive. Means are provided for operating the rods 75 either manually at will or automatically. Such means are similar to the means provided for operating the rods 42. The rods are operated at will by means of hand levers 77 at each side of the machine carried by a trans-

verse rock-shaft 78, which shaft also carries at each side of the machine a downwardly extending arm 80 which is connected by a link to one arm of a lever 81, the other arm of which lever extends downward to engage a collar 82 on one of the rods 75, so that when either of the hand levers 77 is thrown to the left in Figs. 1 and 2 the rods 75 will be moved to the left so as to force the upper ends of the connecting rods 76 and the forward ends of the movable track sections 11 at the several stations C to J inclusive upward for causing carrier drums which may be at any one or more of such stations to move forward to the next station.

For operating the rods 75 automatically, electromagnets 85 and 86, similar to the magnets 50 and 51, are provided one at each side of the machine for each of the rods 75. Such magnets which may be of the single spool form shown with hollow cores through which the rods 75 pass, operate to shift the rods by attracting when energized suitable armatures which are shown as formed by the collars 82. The circuits to magnets 85 and 86 are controlled from the timing mechanism through contact closing means which is caused to be operated by the timing mechanism whenever a carrier drum is in position at either of the stations C to J inclusive. Such contact closing mechanism is shown in Figs. 1 and 2 and in detail in Figs. 10 to 13. As shown in the drawings, a movable contact arm 88 is carried by a short shaft 89 which also carries a segment gear 90 and is mounted in an arm 91 pivoted on a shaft 92. The arm 91 normally stands in the position shown in Fig. 11, and the contact arm 88 is normally held in the position shown in this figure by means of a weighted arm 93. The segment gear 90 is adapted to engage the driving gear 58 of the timing mechanism, but it is held out of engagement therewith when the parts are in the position shown in Fig. 11. The shaft 92 also carries an arm 95 which extends rearwardly and upwardly inside the inner side plate 13 on the near side of the machine in position, as shown in Fig. 13, to be engaged and depressed by the trunnion of a carrier drum falling into position on the supporting and driving disks at the station C. A similar rearwardly extending arm 95 is provided at each of the stations D to J inclusive, and the shaft on which each such arm is mounted at each of such stations also carries a downwardly extending arm 97 similar to the arm 91, and the lower ends of the several arms 97 and the arm 91 are connected by a horizontally extending connecting rod 98 so that when any one of the arms 95 is depressed by a carrier drum coming into position at any one of the stations C to L, the arm 91 will be thrown forward, or to the left in Fig. 2, and such forward movement of the

- arm 91 will be sufficient to carry the segment gear 90 into engagement with the continuously rotating driving gear 58. By such engagement of the gear 90 with the gear 58 the contact arm 88 will be swung upward, and such movement will be continued until a contact piece 100 carried by the arm 88 comes into engagement with a stationary contact piece 101. By such engagement of these two contact pieces circuits including a battery 102 and the magnets 85 and 86 will be completed. The stationary contact piece 101 is connected, as shown in Figs. 1, 2 and 12, with one pole of the battery 102 by wire *p*, and the magnets 85 and 86 are connected in multiple with the other pole of the battery through wire *q* and with the contact piece 100 through wire *r*.
- 20 By the closing of the circuits the magnets will be energized and will attract the armatures 82 on the rods 75, thus moving the rods to the left in Figs. 1 and 2, and causing the movable track sections 11 at each 25 of the stations C to J to be elevated as shown in Fig. 13 and the drum or drums at any one or more of such stations to be advanced to the next station or stations. When the track sections 11 are thus lifted to raise the 30 carrier drums which may be at any one or more of the stations C to J, the arms 95 will be allowed to swing upward and the arm 91 and arms 97 to swing back to normal position under the influence of gravity or 35 of a suitable retracting spring so that the segment gear 90 will be disconnected from the driving gear 58 and the contact piece 100 on the arm 88 will be drawn out of engagement with the stationary contact piece 101, breaking the circuit to the magnets 85 and 86. The arm 88 will then swing back under the influence of the weighted arm 93 to the position shown in Fig. 11, and the 40 parts of the timing mechanism for the stations C to J and the devices which set it in operation when a drum comes to any one of these stations will thus be returned to normal position ready to operate again when a drum comes to position at any one 45 of these stations. A carrier drum coming to the station C will thus be automatically advanced from the station C to the station D and then to and from the station E and the remaining stations, resting at each station 50 while the arm 88 is being moved by the clock movement and until the contact pieces 100 and 101 are in engagement to close circuit to the magnets 85 and 86. If several drums are passing through the machine at the same time, they will be shifted 55 from station to station together, maintaining their relative positions until they are successively advanced from the last washing station. It is not necessary to provide for 60 varying the time that the drums rest at these 65 fixing and washing stations, and a fixed time or period of three minutes will be found suitable, although a longer or shorter period may be provided for if desired.
- It will be noted that, after the magnets 70 have been energized to raise the movable track sections at the station B and at stations C to J, the magnet circuits are almost immediately broken again. In order to prevent the track sections from dropping back 75 to the positions shown in Figs. 1 and 2 so quickly as to interfere with the onward movement of the carrier drums to the adjacent stationary track sections, means are provided for checking or delaying the downward 80 movement of the movable track sections. For this purpose, checking devices are shown at 105 for checking or restraining the return movement of the operating rods 42 under the influence of springs 106. 85 Such check devices may be of any suitable form, such as the common one-way pneumatic checks shown, and will be arranged and adjusted so as not to interfere with the movement of the rods 42 to the left under 90 the influence of the magnets, but so as to restrain or retard the return movement of the rods to delay the downward movement of the track sections 11 at the station B sufficiently to insure the movement of any carrier 95 drum which has been raised by these track sections on to the adjacent stationary track sections 10. Similar pneumatic check devices 110 are shown for similarly restraining the return movement of the rods 75, and thereby delaying for the same purpose the 100 downward movement of the movable track sections at the stations C to J.
- When the operating rods 75 are moved to the left for raising the track sections connected thereto, the rod at the near side of the machine also acts to raise the first light door 115. This door is a vertically sliding door mounted to normally close an opening 116 in the end wall or partition 117 at the 110 end of the dark room or developing chamber beyond the last washing station in the machine shown, through which opening the carrier drums pass from the developing chamber. The door 115 is raised by means of a cord 118 which passes upward from the door over the guide pulleys 119 and 120, thence downward at one side to a large pulley 121 the shaft of which carries a small pulley 122 on which is wound a cord 123 115 which passes downward between guide pulleys 124 and is attached to the end of the rod 75 at the near side of the machine. When this rod 75 moves to the left, therefore, the cord 123 will be drawn from the 125 pulley 122 to rotate that pulley and the pulley 121, and this rotation of the pulley 121 will cause the cord 118 to be wound thereon, thereby raising the door 115 to permit the 130 passage of the carrier drum which was at

the station J when the magnets 85 and 86 were energized.

In order to prevent the door 115 after having been raised from closing too soon and preventing the passing of the drum through the opening 116, a catch 125 is provided to hold the door in its raised position until the catch is tripped to release the door and permit it to close behind the passing drum. The catch is tripped by the carrier drums which pass through the opening 116. When a drum has passed through the opening, one of its end disks will engage and push upward a rearwardly extending tail piece 126 carried by the catch, thereby swinging the catch on its pivot and retracting it to release the door and allow it to close behind the drum. If there should be no drum at the last washing station when 20 the rods 75 are operated to elevate the movable track sections and raise the door 115, the door will then be held in its open position until a drum is advanced from the last washing station and passes through the opening 116, light being meanwhile shut out from the developing chamber by a second vertically sliding light door 130.

The second light door 130 normally closes an opening 131 in a wall or partition 132 beyond the partition wall 117 and distant therefrom a distance greater than the diameter of the carrier drums. The space between the walls 117 and 132 is closed to form an intermediate dark chamber or vestibule so that light will be cut off from the developing chamber when either one of the doors 115 or 130 is closed. The door 130 is raised by operating means which is controlled so that the door will be raised only 40 when the door 115 is closed. Such operating means as shown comprises an electromagnet 133 which is shown as of the single spool hollow core form, and which operates to attract an armature 134 mounted on a 45 rod which is guided to pass through the core of the magnet. A flexible cord 135 extends from the armature around a guide roll 136 and is fastened to a small pulley or drum 137 on a shaft which also carries a large 50 pulley 138, to which is fastened a cord 139 extending upward over suitable guide pulleys, one of which is shown at 140 in Fig. 2, and thence downward to the door 130, in like manner as the cord 118 which is connected to the door 115 as shown in Fig. 14. When the magnet 133 is energized, the cord 135 is drawn from the pulley 137, thereby 55 rotating the pulleys 137 and 138 and causing the cord 139 to be wound on the pulley 138 and drawn downward to raise the door 130 to the position shown in Fig. 2.

The circuit by which the magnet 133 is energized from a battery 140 or other suitable source of electrical energy includes two 60 separate contact closing devices or means,

one controlled by the first light door 115, and the other by the carrier drums passing the door 115. Both of these contact devices must be closed in order to close the magnet circuit. The contact device controlled by 70 the door 115 includes two terminals 141 and 142 connected in the magnet circuit, and a contact closing piece 143 carried by the door 115 and adapted to enter between and close the circuit across the terminals 141 and 142 75 when the door reaches its closed position. The contact device controlled by the passing carrier drums includes a contact piece 144 formed by or carried by the lower end of a lever 145 and a stationary contact piece 80 146 mounted in position so that when the lever 145 is in its normal position, as shown by dotted lines in Fig. 2, the circuit will be broken between these two contact pieces, and when the lever 145 has been thrown by 85 a carrier drum which has passed through the opening 116 to the position shown by full lines in Fig. 2, the contact piece 144 will have been moved into electrical engagement with the contact piece 146. With this arrangement of contact devices, the circuit to the magnet 133 will be normally opened even when the door 115 is closed. When the door 115 is raised, the circuit will be 90 open at two points, and will then remain 95 open until a carrier drum passes through the opening beneath the door. The passing drum will then throw the lever 145 over from its normal position to the position shown by full lines in Fig. 2, thereby closing one break in the magnet circuit. The magnet will not be energized, however, until the door 115, which has been released by the tripping of the catch 125, is fully closed behind the passing carrier drum. When the 100 door reaches its lowermost position, the other break in the magnet circuit will be closed and the magnet will be energized to attract its armature 134 and raise the second light door 130 to permit the drum to 110 pass on through the opening 131 into the drying chamber beyond the wall 132.

When the second light door has been thus raised, it will remain in its raised position until the magnet circuit is again 115 broken to deenergize the magnet. This is accomplished through the movement of a lever 147 which is mounted on the frame 14, and which is connected by a link 148 with the lever 145, so that when the lever 145 120 stands in the position shown in full lines in Fig. 2, the upper end of the lever 147 will project upward in position to be struck by the trunnion of the carrier drum passing the door 130. When this lever 147 is struck 125 by the trunnion of the drum, it will be thrown to the position shown by dotted lines in Fig. 2, and the lever 145 will be thrown back to its normal position and the contact piece 144 moved away from the 130

contact 146 to break the magnet circuit. The magnet will thus be deenergized and the door 130 will drop to close the opening 131.

5 The films on the carrier drums which have passed from the developing chamber past the two light doors will preferably be allowed to remain on the carrier drums until dry. After passing the second light door, 10 the drums may be removed by hand or otherwise to a suitable place for drying the films. Preferably, however, the chamber or space immediately beyond the second partition 132 forms a drying chamber, one end 15 of which is indicated in Fig. 4, and the tracks 14 extend into this drying chamber so that the carrier drums, after passing the second light door 130, will immediately enter the drying chamber and be supported 20 therein on the tracks 14. Light need not, of course, be shut out from this chamber, and the drums may rest on the tracks 14 during the whole time required for drying, or 25 may be shifted or handled in any suitable manner.

The tanks *a*, *b*, *c*, *d* and *e* at the preliminary wetting station, the developing station and the fixing stations, as shown in Figs. 3, 4, 6 and 7, are of elongated trough-like 30 form curved to correspond with the curvature of the carrying surface of the drums, and are mounted at their respective stations in position so that a drum resting on the supporting and driving disks will rotate 35 with the lower portion of its film carrying surface dipping into and passing through the liquid in the tank, as shown in Fig. 7. The edges of the tanks extending parallel to the axis of rotation of the drums are 40 curved upward and inward as shown at 150 above the surface of the liquid in the tank so as to avoid or reduce to a minimum the splashing of liquid from the tanks. The tanks *b*, *c*, *d* and *e* are each provided with 45 a chamber or passage 151 through which cooling water may flow in contact with the under surface of the bottom of the tank for cooling the liquid contained in the tank. 50 A single long tank *f* is provided for containing water for washing the films on drums rotating at the five washing stations F, G, H, I, J. This tank may be of any suitable form, but is preferably a shallow tank mounted as shown in Fig. 4 so that the 55 drums at these several washing stations will rotate with their film carrying surfaces dipping into the water contained in the tank.

In order to prevent any fixing solution which might be thrown from the fixing tank 60 *c* from striking the film on a carrier drum at the developing station or from reaching the developing tank, a splash guard 152 is provided pivotally mounted adjacent to the edge of the developing tank and held yield- 65 ingly in position, as by a weighted arm 153,

so that it may be swung downward out of the way by the end disks of carrier drums passing from the developing station to the fixing station C. A similar splash guard 154 extending upward from the preliminary 70 wetting tank *a* protects film on a carrier drum at the station A from developer which might be thrown from the tank *b*.

Water is supplied to the preliminary wetting tank *a* and to the washing tank *f* and 75 to the cooling chambers of the developing and fixing tanks through a pipe 155 which leads preferably from constant level supply tank 156. Water flows to one end of the tank *a* through a branch pipe 157 and es- 80 capes from the other end of the tank through an outlet pipe 158 which opens to the tank at a proper point to maintain the desired water level in the tank. A valve 160 be- 85 tween the supply tank and the branch 157 tank *a* serves to cut off or regulate the flow of water from the supply tank, and a valve 161 in the branch 157 controls the supply to the tank *a*. Each of the cooling chambers 150 of tanks *b*, *c*, *d*, *e* is connected with the sup- 90 ply pipe 155 by a branch pipe 162 leading to one end of the cooling chamber, and each chamber is provided with an outlet pipe 163 leading from the other end thereof to a pipe 164 through which the water from the se- 95 veral cooling chambers flows to one end of the washing tank *f*. An outlet pipe 165 leads from the other end of the washing tank, and opens thereto at the proper level 100 to maintain the desired water level in the tank.

Developing solution is supplied to the developing tank *b* from a supply tank 170 through a pipe 171 which leads to one end 105 of the developing tank. The tanks *c*, *d* and *e*, which in the machine shown are all in- tended to be fixing tanks, are supplied with fixing solution from a supply tank 172 through pipes 173, one of which leads to 110 one end of each of the fixing tanks. From the end of each of the tanks *b*, *c*, *d* and *e*, opposite to that at which the inlet pipe en- 115 ters the tank, an outlet or overflow pipe 175 leads to a common discharge pipe 176. The overflow pipes 175 open to the tanks at the proper level to maintain the desired level of the solution in the tanks, and each tank is preferably provided also with a drain pipe 177 for draining the tanks empty of solu- 120 tion when desired. Each of these drain pipes is provided with a valve 178 which will be closed when the machine is in opera- 125 tion.

The developer supply pipe 171 is provided with an inlet valve 180 which is normally closed to cut off the flow of developing solution and which is automatically opened to permit developing solution to flow through the developing tank when a carrier drum comes to position at the developing 130

station. Such automatic opening of the valve 180 is secured by connecting the valve stem with an arm 181 carried by a shaft 182 which also carries an arm 183 extending inside the side frame 13 at the far side of the machine, as shown in Fig. 1, in position to be engaged and depressed by the trunnion of a carrier drum coming to position at the developing station. When the arm 183 is so depressed, the arm 181 will be moved downward to open the valve 180. Developing solution will then be supplied to one end of the developing tank and escape from the other end thereof so long as the carrier drum remains at the developing station, and when the carrier drum is lifted and moves onward from the developing to the first fixing station, the arm 183 will be released and the shaft 182 will be rocked back under the influence of suitable means such as the weighted arm 184 to close the inlet valve 180. Developing solution will thus be supplied to the developing tank during all the time that a carrier drum is in position at the developing station, and a constant supply of fresh solution during the development of films will thus be secured, and when there is no carrier drum at the developing station, the supply of solution to the developing tank will be cut off.

It is desirable to provide for diluting the developing solution with water to vary its strength, and especially to decrease the strength of the solution as the time of development is increased. A pipe 185 running from the water supply pipe 155 to the pipe 171 is therefore provided for supplying water to mix with the developing solution flowing from the tank 170. The amount of water flowing through this pipe 185 is controlled by a valve 186, and a valve 187 is provided in the pipe 171 between the supply tank and the point where the water pipe joins pipe 171 for controlling the flow of developer from the tank. A check valve 188 serves to prevent water flowing to the tank 170 when the valve 180 is closed, and in case the water pressure should be sufficient to cause such flow. A valve 189 in the pipe 171 below the pipe 185 serves to cut off or regulate the amount of developing solution flowing to the developing tank when the valve 180 is open.

For automatically regulating the dilution of the developing solution so that a weaker developing solution will be supplied to the developing tank as the time of development for which the timing mechanism is set is increased, the valve 186 is provided with an operating arm 190 connected by a link 191 with a lever 192 carried by a shaft 193 which extends across the machine and carries on the near side of the machine a segment gear 194 which meshes with a seg-

ment gear 195 formed on the hub of the 65 adjustable pivoted arm 68 of the timing mechanism. These parts and connections are so arranged that when the arm 68 is moved over to the right in the drawings to increase the time of development, the valve 70 186 will be operated to increase the flow of water to the developer supply pipe 171, and as the arm 168 is moved to shorten the development period the supply of water to be mixed with the developer will be cut 75 down. The strength of the developer will thus be automatically regulated according to the time of development, a stronger developer being supplied for a short development period and a weaker developer as the 80 development period is increased. By means of the valves 187 and 189, also, the strength of the solution for any development period, and the amount of developing solution supplied to the tank may be varied. 85

In order that the fixing solution shall be supplied to each of the tanks *c*, *d* and *e* only when a carrier drum is in position to be acted on thereby, each of the supply pipes 173 is provided with a normally closed 90 valve 200 similar to the valve 180 of the developer supply pipe, and each of these valves is opened when a carrier drum comes to rest at the corresponding fixing station by means of an arm 201 connected to the valve stem 95 and carried by a rock shaft 202 which also carries an arm 203 extending in position to be engaged and depressed by the trunnion of the carrier drum to open the valve. When the carrier drum is raised and passes 100 on to the next station, the arms 201 and 203 and shaft 202 return to their normal position under the influence of a weighted arm 204 to close the valve 200. Valves 205 are also provided in each of the supply pipes 173 for independently controlling the flow of fixing solution to each of the fixing tanks. 105

Referring now to the winding mechanism for winding the long moving picture films or other long films on the carrier drums at the station A, such mechanism as shown in Figs. 1, 2, 4, 5 and 15 of the drawings comprises a carriage 210 mounted to travel on two slide bars or rods 211 and extending across the machine at the front or starting 110 end thereof. The carriage is provided with means for rotatably supporting a reel or spool 213 carrying a film rolled thereon, and with two guide rolls 214 and 215. The film is passed from the reel up between the guide 115 rolls and then about the roll 215 and upward to the top of a carrier drum supported at the station A. The end of the film may be fastened to the drum by a hook or clip engaging one of the bars 17 of the 120 drum or in any other suitable manner. The guide roll 215 is carried by a swinging arm 216 so as to be movable toward and away 125

from the roll 214, and is pressed toward the roll 214 by means of a weighted arm 217. The roll 215 may thus be moved away from the roll 214 to permit the film to be passed 5 between the rolls, and when released the roll 215 will be pressed toward the roll 214 to grip the film and provide the friction necessary to secure an even winding of the film in the drum under a slight strain or 10 pull sufficient to insure its lying flat on the surface of the drum after it becomes wet. The roll 215 is provided with guiding flanges as shown in Fig. 15, and in order to avoid contact with and possible scratching 15 or other damage to the sensitized surface of the film as it passes between the rolls 214 and 215, the peripheral surface of the roll 214 is cut away as shown in Fig. 15 to leave two narrow edge gripping flanges so that 20 the film will be engaged by the roll 214 only at its edges, and the central portion and nearly all of the sensitized surface of the film will not be touched as the film passes between the guide rolls. 25 For moving the carriage on its rods 211, the roll 214 is journaled on a sleeve as shown in Fig. 15 which runs over about a threaded rod 218 extending between the side frames 13 parallel to the rods 211, and the roll 214 30 carries a finger or nut 219 which engages the thread of the rod 218, so that as the roll is rotated by the film passing from the reel to the rotating carrier drum at the station A, the finger or nut 219 running in the 35 thread of the rod 218 will cause the carriage to move slowly along the rods, and the film will be wound spirally on the drum as indicated in Fig. 5. The pitch of the thread on the rod 218 and the diameter of the guide 40 roll 214 should be such that the carriage will move a distance equal to or but slightly greater than the width of the film at each rotation of the carrier drum. The film will run from the guide rolls to the drum at a 45 slight angle to the perpendicular to the axis of rotation of the drum, and in order that the film shall draw true from the guide rolls, the guide rolls are mounted with their axes slightly inclined to the axis of the 50 drum, and this result is secured in the machine shown by setting the slide rods 211 and the threaded rod 218 at a slight angle to the axis of rotation of the drum. To move the carriage back to starting position, 55 it is only necessary to lift the finger or nut 219 from the threaded rod and slide the carriage back to the desired position.

The operation of the machine will be understood from the foregoing description, 60 and need not be further set forth.

It will be understood that the invention is not to be limited to the exact construction, arrangement, and combinations of parts of the complete machine shown in the

drawings and to which the foregoing description has been in large part confined, but that it includes changes and modifications thereof within the claims. 65

It will also be understood that features of the invention may be used independently 70 of other features thereof, and in machines differing widely from that shown in the drawings.

What is claimed is:

1. In a machine for developing photographic films, the combination of a developing tank, a fixing tank, a carrier drum adapted to support films on its peripheral surface, a guideway for guiding the carrier drum from the developing tank to the fixing 80 tank, and means for moving the carrier drum over the guideway from the developing tank to the fixing tank. 75

2. In a machine for developing photographic films, the combination of a developing tank, a fixing tank, a carrier drum adapted to support films on its peripheral surface, a guideway for guiding the carrier drum from the developing tank to the fixing 85 tank, and automatically operated means for moving the carrier drum over the guideway from the developing tank to the fixing tank. 90

3. In a machine for developing photographic films, the combination of a developing tank, a fixing tank, a film carrier, carrier 95 supporting means at the developing tank, carrier supporting means at the fixing tank, and carrier supporting and shifting means for moving the film carrier from the supporting means at the developing tank to the 100 supporting means at the fixing tank. 100

4. In a machine for developing photographic films, the combination of a developing tank, a fixing tank, a film carrier, carrier supporting means at the developing tank, 105 carrier supporting means at the fixing tank, carrier supporting and shifting means for moving the film carrier from the supporting means at the developing tank to the supporting means at the fixing tank, means for operating said supporting and shifting means automatically, and means for operating the supporting and shifting means manually. 110

5. In a machine for developing photographic films, the combination of a developing tank, a fixing tank, a film carrier, carrier 115 supporting means at the developing tank, carrier supporting means at the fixing tank, carrier supporting and shifting means for moving the film carrier from the supporting means at the developing tank to the supporting means at the fixing tank, and timing mechanism for controlling the operation of said supporting and shifting means. 120

6. In a machine for developing photographic films, the combination of a developing tank, a fixing tank, a film carrier, a 125 guideway for guiding the film carrier from

- the developing tank to the fixing tank, means for moving the film carrier over the guideway from the developing tank to the fixing tank, and timing mechanism for controlling the operation of said carrier moving means, said timing mechanism being adjustable for varying the time that a film carrier remains at the developing tank.
7. In a machine for developing photographic films, the combination of a developing tank, a fixing tank, a film carrier, carrier supporting means at the developing tank, carrier supporting means at the fixing tank, carrier supporting and shifting means for moving the film carrier from the supporting means at the developing tank to the supporting means at the fixing tank, and automatically controlled means for operating said supporting and shifting means.
10. 8. In a machine for developing photographic films, the combination of a developing tank, a fixing tank, a film carrier for carrying a film detachably secured thereto, means for shifting the film carrier from the developing tank to the fixing tank, electrically operated means for operating said shifting means, a timing mechanism for controlling the operation of said electrically operated means, and means adapted to be controlled by the film carrier for setting said timing mechanism in operation.
9. In a machine for developing photographic films, the combination of a series of tanks including a developing tank and one or more fixing tanks and a washing tank, a film carrier, carrier supporting means at each tank, and carrier supporting and shifting means for shifting the film carrier from the developing tank to a fixing tank and from a fixing tank to the washing tank.
10. In a machine for developing photographic films, the combination of a series of tanks including a developing tank and a plurality of fixing tanks, a film carrier, carrier supporting means at each tank, carrier supporting and shifting means for shifting the film carrier from the developing tank to the first fixing tank and to the remaining fixing tank or tanks, timing mechanism for controlling the operation of said supporting and shifting means, and means for regulating the timing mechanism for varying the time that a film carrier remains at the developing tank.
11. In a machine for developing photographic films, the combination of a developing tank, a fixing tank, a film carrier, means for shifting a film carrier from the developing tank to the fixing tank, timing mechanism for controlling the operation of said shifting means, said timing mechanism being adjustable for varying the time that a film carrier remains at the developing tank, and automatically operated means for varying the strength of the developing solution
- according to the time of development for which the timing mechanism is set.
12. In a machine for developing photographic films, the combination of a developing tank, a fixing tank, a film carrier, means for shifting a film carrier from the developing tank to the fixing tank, and automatically operated means for supplying developing solution to the developing tank only while a film is at the developing tank.
13. In a machine for developing photographic films, the combination of a developing tank, one or more fixing tanks, a washing tank, a film carrier, means for shifting the film carrier from the developing tank to a fixing tank, means for shifting the film carrier from a fixing tank to the washing tank, a cooling chamber for the developing tank, and means for causing water to flow through said cooling chamber and thence to the washing tank.
14. In a machine for developing photographic films, the combination of a film carrier, supporting means therefor, means for supplying a liquid for acting on film on the carrier when supported by said supporting means, and means controlled by the carrier for causing said liquid to be supplied only when the carrier is supported by said supporting means.
15. In a machine for developing photographic films, the combination of a film carrier, a tank, means for supporting the carrier in position to have film carried thereby acted upon by liquid in the tank, and means controlled by the carrier for supplying liquid to the tank.
16. In a machine for developing photographic films, the combination of a film carrier, a tank provided with an inlet and an outlet, means for supporting the carrier in position to have the film carried thereby acted upon by liquid in the tank, automatically operated means for controlling the flow of liquid through the tank inlet to admit liquid to the tank only when a carrier is supported by said supporting means.
17. In a machine for developing photographic films, the combination of a carrier drum adapted to support films on its peripheral surface, a tank, supporting means for supporting and rotating the carrier in position so that its film carrying surface will move through liquid contained in the tank, the bottom of the tank being close to the path of movement of the carrying surface of the carrier drum and being curved to correspond substantially to the curvature of the carrying surface of the carrier drum, and means for supplying liquid to one end of the tank, the tank having an outlet from the other end.
18. In a machine for developing photographic films, the combination of a carrier drum adapted to support films on its periph-

5 eral surface, a tank, supporting means for supporting and rotating the carrier in position so that its film carrying surface will move through liquid contained in the tank, and automatically operated means for supplying liquid to the tank.

19. In a machine for developing photographic films, the combination of a carrier drum adapted to support films on its peripheral surface, a tank having an inlet and an outlet, supporting means for supporting and rotating the carrier in position so that its film carrying surface will move through liquid contained in the tank, and means operated by the carrier drum for controlling the flow of liquid through the inlet to the tank.

20. In a machine for developing photographic films, the combination of a carrier drum adapted to support films on its peripheral surface, a tank, supporting means for supporting and rotating the carrier in position so that its film carrying surface will move through liquid contained in the tank, and means for removing the carrier drum from said supporting means at the end of a predetermined period.

21. In a machine for developing photographic films, the combination of a carrier drum adapted to support films on its peripheral surface, a tank, supporting means for supporting and rotating the carrier in position so that its film carrying surface will move through liquid contained in the tank, shifting means for removing the carrier drum from said supporting means, timing mechanism for controlling the operation of said shifting means, and means for starting said timing mechanism in operation when the drum carrier comes to position on said supporting means.

22. In a machine for developing photographic films, the combination of a carrier drum adapted to support films on its peripheral surface, a tank, supporting means for supporting and rotating the carrier in position so that its film carrying surface will move through a liquid solution contained in the tank, timing mechanism for controlling the operation of said shifting means, said timing mechanism being adjustable to vary the time that the carrier drum remains at the supporting means, means for supplying a liquid for diluting the strength of the solution as it flows to the tank, and means for automatically controlling the operation of the means for supplying the diluting liquid according to the adjustment of the timing mechanism.

23. In a machine for developing photographic films, the combination of a carrier drum adapted to support films on its peripheral surface, means for advancing the carrier drum bodily, and means for subjecting film on the carrier drum successively to

the action of developing solution and fixing solution.

24. In a machine for developing photographic films, the combination of a film carrier, a plurality of stations each provided with devices for supporting a film carrier, track sections between the stations, and means for causing a film carrier to travel on said track sections from station to station.

75 25. In a machine for developing photographic films, the combination of a film carrier for carrying a film detachably secured thereto, means for advancing the film carrier bodily, means for subjecting film on the carrier successively to the action of developing solution and fixing solution, means for varying the time the film on the carrier is subjected to the action of the developing solution, and automatically operated means for varying the strength of the developing solution according to the time that the film is subjected to the action of the same.

26. In a machine for developing photographic films, the combination of a film carrying drum, means for advancing the carrying drum bodily, and means for subjecting film carried by the drum successively to the action of developing solution, fixing solution and a washing liquid.

95 27. In a machine for developing photographic films, the combination of a film carrier for carrying a film detachably secured thereto, means for advancing the film carrier bodily, means for wetting the film on the carrier, means for subjecting the wet film on the carrier successively to the action of developing solution and fixing solution, and means for operating the carrier to subject successive portions of film carried thereby to the action of the developing and fixing solutions.

100 28. In a machine for developing photographic films, the combination of a film carrier for carrying a film detachably secured thereto, means for advancing the carrier successively from each of a plurality of resting stations, means for subjecting film on the carrier to the action of a developing solution at one of said stations, means for subjecting the film to the action of a fixing solution at another of said stations, and means for operating the carrier to cause successive portions of the film to be subjected to the action of the developing and fixing solution.

110 120 29. In a machine for developing photographic films, the combination of a film-carrying drum, means for advancing the carrying drum successively from each of a plurality of resting stations, means for subjecting film on the carrying drum to the action of a developing solution at one of said stations, means for subjecting the film to the action of a fixing solution at another of said stations, means for rotating the car- 125 130

rying drum during the developing and fixing operations, and means for washing the film at another of said stations.

30. In a machine for developing photographic films, the combination of a film carrier for carrying a film detachably secured thereto, means for advancing the carrier successively from each of a plurality of resting stations, means for wetting the film at 5 one of said stations, means for subjecting the film to the action of a developing solution at one of said stations, means for subjecting the film to the action of a fixing solution at another of said stations, means for 10 washing the film at another of said stations, and means for operating the carrier to subject successive portions of the film to the action of the wetting, developing and fixing solutions.
20. 31. In a machine for developing photographic films, the combination of a film-carrying drum, automatically operated means for advancing the carrying drum successively from each of a plurality of 25 resting stations, means for subjecting film on the drum to the action of a developing solution at one of said stations, means for subjecting the film to the action of a fixing solution at another of said stations, and 30 means for rotating the drum during the developing and fixing operations.
32. In a machine for developing photographic films, the combination of a film-carrying drum, automatically operated 35 means for advancing the carrier drum successively from each of a plurality of resting stations, means for subjecting film on the drum to the action of a developing solution at one of said stations, means for 40 subjecting the film to the action of a fixing solution at a plurality of said stations, means for rotating the drum while at said stations, and adjustable means for varying the time that the drum remains at the 45 developing station.
33. In a machine for developing photographic films, the combination of a film-carrying drum, a plurality of stations each provided with a tank and with drum supporting 50 means for supporting and rotating the drum in position to have film carried thereby acted on by the liquid in the tank, and means for advancing the drum successively from station to station.
55. 34. In a machine for developing photographic films, the combination of a carrier drum adapted to support films on its peripheral surface, a plurality of stations each provided with a tank and with supporting 60 means for supporting and rotating the carrier in position so that its film carrying surface will move through liquid contained in the tank, and means for advancing the carrier successively from station to station.
65. 35. In a machine for developing photo-

graphic films, the combination of a film-carrying drum, a plurality of stations each provided with drum-supporting and rotating means, drum advancing means at each station, means for operating the drum advancing means automatically at predetermined intervals, means for subjecting films on the drum to the action of a developing solution at one of said stations, and means for subjecting the films to the action of a fixing solution at another of said stations.

36. In a machine for developing photographic films, the combination of a film carrier, a plurality of stations each provided with carrier supporting and operating 80 means, carrier advancing means at each station, means for operating the carrier advancing means automatically at predetermined intervals, means for operating the carrier advancing means at will, means for 85 subjecting film on the carrier to the action of a developing solution at one of said stations, and means for subjecting the film to the action of a fixing solution at another of said stations.

37. In a machine for developing photographic films, the combination of a film carrier, a plurality of stations each provided with carrier supporting means, carrier advancing means at each station, means for 90 subjecting film on the carrier to the action of a developing solution at one of said stations, means for subjecting the film to the action of fixing solution at a plurality of 95 said stations, operating means for operating the carrier advancing means at the developing station, adjustable timing mechanism for controlling the operation of said operating means, and independent operating means for simultaneously operating the 100 carrier advancing means at the several fixing stations.

38. In a machine for developing photographic films, the combination of a film carrying drum a plurality of stations each 110 provided with devices for supporting and rotating a carrier drum, track sections between the stations, and means for causing a carrier drum to travel on said track sections from station to station.

39. In a machine for developing photographic films, the combination of a plurality of film carrying drum stations each provided with supporting devices for supporting and rotating a carrier drum, inclined track sections between the stations, and a lifting device at each station for lifting the carrier drum from the supporting devices and causing it to roll on the inclined track section to the next station.

40. In a machine for developing photographic films, the combination of a plurality of film carrying drums, a developing station and a plurality of stations beyond the developing station including one or more 130

- fixing stations, supporting devices at each of said stations for supporting and rotating a carrier drum, inclined track sections between the stations, a lifting device at each station 5 for lifting the carrier drum from the supporting devices and causing it to roll on the inclined track section to the next station, means for operating the lifting devices at the stations beyond the developing station 10 simultaneously, separate means for operating the lifting device at the developing station, and an adjustable timing mechanism controlling the said means for operating the lifting device at the developing station.
- 15 41. In a machine for developing photographic films, the combination of a plurality of film carrying drums, a plurality of stations each provided with a tank and with supporting devices for supporting and rotating a carrier drum in position so that its film carrying surface will move through liquid contained in the tank; means for supplying developing solution to the tank at one of said stations, means for supplying 20 fixing solution to the tanks at one or more of said stations, track sections between the stations, means for causing the carrier drums to travel on said track sections from station to station, and means controlled by 25 the carrier drums for controlling the supply of developing solution to the tank at the developing station.
42. In a machine for developing photographic films, the combination of a plurality of film carriers, a dark room, means for simultaneously advancing a plurality of film carriers in and from the dark rooms, means for subjecting film on each carrier successively to the action of developing and fixing 30 solution in the dark room, and means for 35
43. In a machine for developing photographic films, the combination of a plurality of film carriers, a dark room, a plurality of stations in the dark room each provided with supporting devices for supporting a film carrier, track sections for the film carrier between the stations, a track section 45 leading from the last station to a point outside the dark room, means for causing the film carrier to travel on said track sections from station to station and from the dark room, a wall of the dark room having an 50 opening for the passage of the film carrier from the dark room, a door for closing said opening, and means for preventing entrance of light to the dark room when said door is open.
44. In a machine for developing photographic films, the combination of a dark room, developing and fixing means in the dark room, a film carrier, means for supporting the carrier during the development 55 and fixing of the film, means for transferring the carrier after the development and fixing of the film from the dark room to a point outside the dark room, and means controlled by the carrier for preventing entrance of light to the dark room during the 60 passage of the carrier therefrom.
- In testimony whereof, I have hereunto set my hand, in the presence of two subscribing witnesses.

WILLIAM F. GARLAND.
